UNITED STATES PATENT OFFICE.

HENRY T. VAN DENBERGH, OF CHICAGO, ILLINOIS, ASSIGNOR TO THE PRO-
GRESS NOVELTY MANUFACTURING COMPANY, OF SAME PLACE.

DESIGN FOR A CABINET.

SPECIFICATION forming part of Design No. 23,002, dated January 9, 1894.

Application filed October 27, 1893. Serial No. 489,318. Term of patent 3½ years.

To all whom it may concern:

Be it known that I, HENRY T. VAN DENBERGH, a citizen of the United States, and a resident of Chicago, in the county of Cook and State of Illinois, have invented and produced a new and original Design for Cabinets, of which the following is a specification, reference being had to the accompanying drawing forming a part hereof.

- 10 This design relates to cabinets for exhibition, storage and other purposes and has for its object to provide a novel and ornamental cabinet which presents to the eye a distinguishing and characteristic appearance.
- 15 The leading feature of the design consists in a casing or body of oblong rectangular form in plan and front view and of quadrangular form in end elevation, the top of the body portion being divided into rectangular 20 panels, one arranged at the center and two at each side thereof, all of which are of the same dimensions and surrounded by a narrow raised beading or frame, and the front of said casing being divided into two longitudinal 25 sections, the upper one having two narrow oblong raised panels extending from near the ends of the casing to near the center thereof where the ends of the panels are curved and between them is interposed a circular raised 30 panel, while the lower part of the front of the casing is divided into sections corresponding in number and location with the sections of the top of the casing, and in each of which sections is located a rectangular sunken panel.
- 35 The design is illustrated in the accompanying drawing, in which the figure is a perspective view of a cabinet embodying the design.

In the drawing, A designates the body portion of the cabinet which is of oblong rectangular form in plan and front view and of quadrangular form in end view. The top of

the cabinet is at an angle or incline to the front thereof, forming an obtuse angle therewith and an acute angle with the back of the 45 cabinet. The top of the cabinet is divided into five rectangular sections of equal dimensions and each section consisting of a panel E surrounded by a narrow raised margin, beading or framing.

The front of the body A of the casing is divided by a straight horizontal bead or molding a extending from end to end of the casing, into two longitudinal sections, and in the upper section or space are placed two 55 raised oblong angular panels d extending from near the ends to near the center of the upper section, the outer ends of each panel being curved outwardly or convexed, and the inner ends of the panels being each concaved to conform to the raised circular panel b interposed between the ends of said panels d. The lower longitudinal section of the casing is divided by narrow vertical strips e into five sections 60 corresponding in width and location with the sections in the top of the casing, and each of said sections contains a sunken oblong rectangular panel C, the inclosing margins of which panels are beveled, the surrounding plain surface of each section giving the 65 appearance of a framing or molding surrounding each of the sunken panels.

The design provides a cabinet for exhibition and storage purposes which presents to the eye an ornamental, distinguishing and 70 characteristic appearance.

What I claim is—

The design for a cabinet herein shown and described.

HENRY T. VAN DENBERGH.
